C. Brown & Co.

Inventor
John H. Wait,

UNITED STATES PATENT OFFICE.

JOHN H. WAIT, OF PORTSMOUTH, OHIO.

STENCH-TRAP.

SPECIFICATION forming part of Letters Patent No. 451,537, dated May 5, 1891.

Application filed May 12, 1890. Serial No. 351,483. (No model.)

To all whom it may concern:

Be it known that I, JOHN H. WAIT, a citizen of the United States, residing at Portsmouth, in the county of Sciota and State of 5 Ohio, have invented a new and useful Stench-Trap, of which the following is a specification.

This invention relates to water-closets and slop-pails, and more especially to the stench-traps used therein; and the object of the invention is to provide a device which will prevent the escape of offensive odors, its construction being an improvement on devices of this general character heretofore existing.

To this end the invention consists of a receptacle having below its open upper end or mouth an annular flange into which is passed a closing-plug having a trap therein of peculiar construction, all as will be hereinafter more fully described, and illustrated in the 20 drawings, in which--

Figure 1 is a central vertical section of an ordinary slop-pail with my improvements attached. Fig. 2 is a side elevation, and Fig. 3 is a section, of one form of plug embodying 25 my invention, the receptacle being shown in dotted lines. Figs. 4 and 5 are respectively a side elevation and section of another form of plug.

Referring to the said drawings, the letter 30 R designates a receptacle, such as an ordinary slop-pail or a public urinal or commode U.

The former is provided with an interior upwardly-extending flange F below its open upper end, which may receive an ordinary cover, if desired, or may be left open. C is the cover referred to, preferably convex, and having a depending annular flange c, adapted to pass into and loosely fit the groove in the flange 35 F, as shown in Fig. 1, said cover being preferably provided with a handle H, whereby it can be removed when it is desired to use the receptacle for other purposes than urinating therein, or when it is desired to empty the 40 contents therefrom. This cover being applied in place with its depending flange c seated in the grooved flange F, if urine or other water be poured upon the convex upper face of the cover it will run down to the periphery of the same and into the groove of the flange F, which it will fill to above the 45 level of the lower edge of the depending flange

c, thereby forming a water seal between the parts and preventing the escape of offensive odors from the interior of the receptacle, as 55 will be clearly understood. Although I have shown and described this cover C, I prefer to use a plug for closing the vessel.

In Figs. 2 to 5 I have shown different forms of plugs which may be used, and these plugs 60 may be of such a size as to be placed directly within the openings in the flange F of the receptacle R, (shown in Fig. 1,) which they will close tightly, as will be understood.

The plug shown in Figs. 3 and 4 consists 65 of a tapered body T, having a handle H at its upper end. This body is provided with a lateral opening O at one side and at such point that it will stand below the flange F, and a central passage P extends downwardly 70 from the upper end of the body nearly to the lower end of the plug, and then turns upwardly into and opens out through the opening O. The urine in this case would flow down such passage and fill the lower end thereof, 75 overflowing through the opening O, and a perfect stench-trap would be formed thereby, the plug being removed when it was desired to use the receptacle for other purposes.

In the construction illustrated in Figs. 5 80 and 6 the tapered portion of the body T of the plug has a reduced and rounded lower end E, and the passage P extends vertically through the body and end, as shown. The lower portion of the body L has a cup-shaped 85 upper end open at each side, as at O, between upwardly-extending ears e, the upper edges of the cup being higher than the lower end of the passage through the end E. The ears e are pivotally connected with the end E, 90 whereby the lower portion L of the plug can be detached for cleaning. This construction of plug is especially useful in connection with portable receptacles R, because when such receptacles are carried from place to place they 95 are likely to be tilted slightly, whereby the water seal in the grooved flange F or in the opening O of the solid plug would be spilled and would flow into the body of the receptacle. This spilling would destroy the efficiency 100 of the trap and allow offensive odors to escape, whereas with this two-part plug the lower member thereof would swing from side to side and a perfect seal would always be main-

tained while the receptacle was being carried about, as will be understood.

I claim as the salient points of this invention—

- 5 1. In a commode, the combination, with the receptacle having an interior annular flange below its upper end, of a plug having a tapered body tightly fitting in said flange, said body being provided with a passage extending downwardly from its upper end and terminating in an open cup which projects above the lower end of the opening, so as to form a seal therefor, and finally opening at the side of the plug below the flange, as and for the purpose set forth.
- 15 2. In a commode, the combination, with the receptacle having an interior annular flange below its upper end, of a plug having a ta-

pered body at its upper portion tightly fitting said flange, the lower end of said body being reduced, said body and lower end being provided with a vertical passage, and a lower portion of said body having a cup-shaped upper end, with ears thereon pivoted to said lower end of the upper portion, the upper 25 edges of the cup standing above the lower end of the said passage and below the flange in the receptacle, all as and for the purpose set forth.

In testimony that I claim the foregoing as 30 my own I have hereto affixed my signature in presence of two witnesses.

JOHN H. WAIT.
